UNITED STATES PATENT OFFICE.

CHARLES WILLIAM JACKSON, OF CHICAGO, ILLINOIS.

DESIGN FOR A FURNITURE-GIMP.

SPECIFICATION forming part of Design No. 16,888, dated September 7, 1886.

Application filed April 29, 1886. Serial No. 200,629. Term of patent 14 years.

To all whom it may concern:

Be it known that I, CHARLES WILLIAM JACKSON, a subject of the Queen of Great Britain and Ireland, residing at Chicago, in the county of Cook and State of Illinois, have invented and produced a new and original Design for a Furniture-Gimp, of which the following is a specification, reference being had to the accompanying drawings, forming a part thereof.

This invention relates to a new design for furniture-gimp; and it consists of a central ornamentation having a series of diagonally-marked prolate hemispheroidal projections, each of said projections forming an acute angle to the right line of said row, and interrupted by diagonally-marked bands or bars at right angles to the right line of said row, the said central ornamentation also having upon each side thereof and parallel thereto a row of ornamentation consisting of a series of similar diagonally-marked prolate hemispheroidal projections, each at an oppositely-inclined acute angle to that of the right line of the said first row, these three lines of ornamentation being also bordered by an outer line of ornamentation similar to the central line, and the whole five lines of ornamentation partially interrupted by diagonally-marked bands or bars at right angles to the right lines of the several rows.

Figure 1 is a face view of my new design, and Fig. 2 is a longitudinal section of the same on line 2 2 of Fig. 1.

Like letters refer to like parts throughout the several views.

A is a row of central ornamentation, consisting of a series of diagonally-marked prolate hemispheroidal projections, each of said projections forming an acute angle to the right line of said row, and interrupted by diagonally-marked bands or bars E at right angles to the right line of said row.

B B are rows of ornamentation on each side of and parallel to the right line of row A, and consisting, likewise, of a series of diagonally-marked prolate hemispheroidal projections at an opposite acute angle to the right line of the row.

C C are duplicates of row A on the outer side of rows B B.

D D are diagonally-marked bands or bars at right angles to the right line of row B.

What I claim, and desire to secure by Letters Patent, is—

The design for a furniture-gimp herein shown and described, consisting of the central row of diagonally-marked prolate hemispheroidal projections, each of said projections forming an acute angle to the right line of said row, like parallel outer rows, B and C, the spheroidal projections of rows B being each at an oppositely-inclined acute angle to that of the right line of the said first row, A, and the diagonally serrated or marked bands or bars E and D at right angles to the right lines of the said first-named series of rows, as shown and described.

CHARLES WILLIAM JACKSON.
